Albert F. Daum.

UNITED STATES PATENT OFFICE.

ALBERT F. DAUM, OF PITTSBURGH, PENNSYLVANIA.

FUSE.

1,150,344.

Specification of Letters Patent.

Patented Aug. 17, 1915.

Application filed May 8, 1912, Serial No. 695,868. Renewed January 28, 1915. Serial No. 4,951.

To all whom it may concern:

Be it known that I, ALBERT F. DAUM, a citizen of the United States, residing at Pittsburgh, in the county of Allegheny and State of Pennsylvania, have invented new and useful Improvements in Fuses, of which the following is a specification.

My invention relates to improvements in fuses and has particular relation to fuses designed for employment in connection with cut-out blocks and switch-boards, and more particularly known as "plug fuses".

The objects of my invention are to provide a fuse of this type which can be readily refilled after being blown; which is formed with a minimum number of parts; which may, if desired, be provided with a detecting mechanism; which is simple and efficient in operation, durable in construction, and which can be manufactured at a relatively low cost.

To these and other ends, the nature of which will be readily understood as the invention is hereinafter disclosed, my invention consists in the improved construction and combination of parts, hereinafter fully described, illustrated in the accompanying drawings, and particularly pointed out in the appended claims.

In the accompanying drawings, in which similar reference characters indicate similar parts in each of the views,—Figure 1 is a central vertical sectional view taken through one form of my device. Fig. 2 is a similar view taken at right angles to the section of Fig. 1. Fig. 3 is a horizontal sectional view. Fig. 4 is a top plan view. Fig. 5 is a vertical sectional view of a modified form. Fig. 6 is a similar view of a further modification. Fig. 7 is a plan view, partly in section of the construction shown in Fig. 6.

The body-portion 10 of my improved fuse is formed of suitable insulating material, such as porcelain, glass, etc., and has its exterior threaded on two planes, as at 11 and 12, each adapted to receive a screw-threaded metallic ferrule as at 13 and 14, respectively, as is common in this type of fuses. In the several modifications of the invention shown herein, however, the body-portion is in the form of a shell, being provided with a central recess 15 extending close to the bottom of the body-portion, leaving a comparatively thin bottom wall, the annular side wall being also relatively thin, thereby providing a relatively large recess centrally of the body-

portion, rendering the bottom of the plug readily accessible for cleaning or repairing purposes, and at the same time providing a large space within which expansion may take place when the fuse blows.

The outer threaded ferrule 14 may, if desired, be in the form of a cap, and I preferably form the cap with a central opening 16 and may locate therebelow a transparent plate member or shield 17, although it is not absolutely essential that either be employed.

I may, if desired, and in the form shown in Figs. 1 to 4 I prefer so to do, provide the inner wall of the plug with an inclined face 18, said face changing the normal circular configuration of the wall of the recess so as to prevent the fuse clamping member from rotating when being secured in position.

The several views show different ways in which the terminals are arranged, Figs. 1 to 4 showing the preferred form in which the fuse extends from the top to the bottom of the recess, the remaining forms showing the fuse as extending from side to side adjacent the top of the recess. In each form, however, one of the fuse terminals is in the form of a plate 20 located in a slot 21 of the body portion and having its lower end soldered or otherwise secured to the lower ferrule 13, the upper end of said plate being bent at an angle and extending into the recess as at 22, as in Figs. 1, 2, 3, 4, 5 and 7, or enlarged as at 22^a in Fig. 6, the enlargement projecting above the bottom of a lateral slot 23, to retain the fuse in position where it is not given a bend which would tend to weaken it. The angular portion 22 or the enlargement 22^a is threaded to receive a screw 24 which acts to clamp the fuse to the terminal.

As will be readily understood, a removal of the cap and of the plate or shield 17 (if the latter be employed) exposes the terminal 20 in such manner as to enable the fuse to be removed or secured as the case may be by loosening or removing the screw 24, placing the fuse in position, and returning the screw to position.

In the form shown in Figs. 1 to 4, the opposite end of the fuse leads to the bottom of the recess, being clamped under a metallic plate 25 by the action of a screw 26 extending through an opening in the bottom of the plug, the inclined face 18 acting to prevent turning of the plate during the securing operation. Owing to the relatively large recess in which the fuse is located, the manipu-

lation of the fuse to place it in position or to remove it can be readily had, a positive advantage since it permits of the formation of a regulation plug fuse configuration with, however, but a minimum number of parts and a maximum space for expansion.

In the form shown in Figs. 5 to 7, the conductor from the screw 26 is in the form of a metallic plate 27 having its ends bent in opposite directions, the lower end being secured in position by the screw 26, while the upper end projects into a slot 28 formed in the wall of the body-portion opposite the slot 23, being preferably held in position by screw 29 threaded therethrough into a socket 30 located in a recess 31 at the bottom of the slot 28: as shown in Fig. 5, the socket may be omitted and the threading be directly on the plate 27. In these forms, the fuse is clamped between the upper end of said plate (which forms the terminal) and the screw 29, and leads directly across the recess. In these latter types, I may employ a detector in the form of an element 31^a carried by a screw or other carrier 32, the latter being normally pressed inwardly by a spring 33 carried by the cap, the element resting on the fuse and being held against the tension of the spring until the fuse blows whereupon the spring causes the element to change its position and thus indicate that the fuse has blown.

As will be readily seen the constructions shown herein are exceedingly simple and provide for the greatest efficiency in operation, are formed of a minimum of parts, can be readily re-filled when blown, which can be manufactured at a relatively low cost, and which is capable of use with any of the standard forms of sockets.

While I have herein shown and described various ways in which my invention may be carried out, it will be readily understood that changes and modifications therein may be required or desired to meet the exigencies of use, and I desire it to be understood that I reserve the right to make any and all such changes and modifications as long as the same fall within the spirit and scope of the invention as expressed in the following claims.

Having thus described my invention, what I claim as new is:

1. In a refillable plug fuse and in combination, a body-portion having a metallic contact exteriorly threaded thereto and having a central recess, said body-portion also having a slot extending laterally through a wall of said recess adjacent the outer end of the body-portion and then inwardly substantially parallel to said recess to a point beyond the outer plane of said contact, said recess being of a depth to place its bottom

beyond the plane of said slot, a terminal secured to said contact and extending through said slot into said recess, a clamping screw carried by said terminal, a removable contact screw at the closed end of the body-portion and projecting into said recess, a plate threaded to said latter screw at the bottom of the recess, and a fuse element having one end secured to said terminal and the other end in electrical connection with said plate.

2. In a refillable plug fuse and in combination, a body-portion having a metallic contact exteriorly threaded thereto and having a central recess, said body-portion also having a slot extending laterally through a wall of said recess adjacent the outer end of the body-portion and then inwardly substantially parallel to said recess to a point beyond the outer plane of said contact, said recess being of a depth to place its bottom beyond the plane of said slot, a terminal secured to said contact and extending through said slot into said recess, a clamping screw carried by said terminal, a removable contact screw at the closed end of the body-portion and projecting into said recess, a plate threaded to said latter screw at the bottom of the recess, a fuse element having one end secured to said terminal and the other end in electrical connection with said plate, a cap threaded to said body-portion, and an indicating device carried by the cap and extending into said recess for indicating the state of the fuse.

3. In a refillable plug fuse and in combination, a body-portion having a metallic contact exteriorly threaded thereto and having a central recess, said body-portion also having a slot extending laterally through a wall of said recess adjacent the outer end of the body-portion and then inwardly substantially parallel to said recess to a point beyond the outer plane of said contact, said recess being of a depth to place its bottom beyond the plane of said slot, a terminal secured to said contact and extending through said slot into said recess, a clamping screw carried by said terminal, a removable contact screw at the closed end of the body-portion and projecting into said recess, a rectangular plate threaded to said latter screw at the bottom of the recess, and a fuse element having one end secured to said terminal and the other end in electrical connection with said plate, a wall of said recess being off-set to co-act with one edge of the plate to position the latter against rotative movement.

ALBERT F. DAUM.
